UNITED STATES PATENT OFFICE.

NEWTON L. GLOVER AND JAMES A. HANSON, OF WINDOM, MINNESOTA.

ELECTRIC BURGLAR DETECTOR.

Application filed February 11, 1924. Serial No. 691,918.

To all whom it may concern:

Be it known that we, NEWTON L. GLOVER and JAMES A. HANSON, citizens of the United States, residing at Windom, in the county of Cottonwood and State of Minnesota, have invented certain new and useful Improvements in Electric Burglar Detectors; and do hereby declare the following to be a full, clear, and exact description 10 of the invention, such as will enable others skilled in the art to which it appertains to make and use the same.

Our invention relates to electric signal apparatus, and has for its principal objects to 15 provide automatic means for control of the electric lights in a building or other location and to provide means for signalling to a more or less distant point or points in case the circuit controlling the said lights is in any 20 manner broken, and has for one of its more important objects to protect the contents of a building from theft by burglars or otherwise.

It is a common practice in banks, stores, or 25 other places where things of value are kept, to provide a light or lights suitably located and continued in operation throughout the night, and thus enabling a patrolman or other persons to see or detect any person or 30 operation within the building or space covered by the lights. A burglar, to avoid such detection, will turn out or disconnect these lights by in some way breaking the electric circuit producing the same.

35 Our invention provides means by which, when the circuit is thus disconnected, a person or persons at a more or less remote location will be apprised of such occurrence by automatically operated signals, and will thus 40 be enabled to capture the burglar or prevent theft of the property.

The preferred form of the invention is illustrated in the accompanying drawings. It is not our purpose to confine ourselves 45 strictly to the specific details shown, inasmuch as slight modifications of form or structure might be made without departing from the spirit of the invention.

Referring to said drawings:

50 Fig. 1 is a diagrammatic view illustrating the invention;

Fig. 2 is a top plan view of an automatic call device; and

55 Fig. 3 is a side elevation of the parts shown in Fig. 2.

The device consists of an electric light cir-

cuit connected in series with one or more night light bulbs and with a timed switch, manually adjustable for setting, and controlled by clock mechanism. In the circuit 60 is incorporated a magnet coil, which coil is adapted for holding open a secondary circuit. The secondary circuit is also in circuit with an adjustable timed switch controlled by clock mechanism and when closed 65 is adapted to ring the bell of a telephone or an ordinary electric bell or control other signal apparatus as will be hereinafter described in detail.

The numerals 4 and 5 indicate the outside 70 or service wires of an ordinary electric lighting circuit, and the numerals 4' and 5' indicate the two wires of the house circuit leading from the service wires and in circuit with the night light. The main wires 75 of the telephone circuit are indicated by the numerals 6 and 7, the house leads by the numerals 6^a and 7^a, and a house lead shunt circuit by the numerals 6' and 7'. The house leads 6^a and 7^a are connected to the telephone in the usual way.

Suitable clock mechanism, not shown, is adapted to rotate the wheels 8 and 8', which are provided with circumferentially adjustable arms 9, 9¹, 9² and 9³, adapted to operate the adjacent arms of levers 10 and 10', which are pivoted on studs 12 and 12' and actuated by springs 13 and 13'. The outer arms of the levers 10 and 10' each carry contact blocks 14 and 14' adapted, when 90 operated by the arms 9 and 9¹, to make electrical contact with fixed contact blocks 11 and 11' and complete the circuit. The blocks 11 and 11' are adapted to latch over and hold the blocks 14 and 14' in contact with 95 the same against the action of the springs 13 and 13'. The plates 15 and 15', pivoted at 16, curved upward in their central portion, and impelled by springs 17, normally 100 rest against the outer edges of the blocks 14 and 14'. The arms 9¹ and 9³ are longer than the arms 9 and 9² and, therefore, operate the levers 10 and 10' through a greater arc, sufficient to permit the plates 15 and 15' to pass beneath the blocks 14 and 14', 105 whereby the said blocks, in returning, are lifted over the latches of blocks 11 and 11', thus permitting the springs 13 and 13' to carry the blocks 14 and 14' out of contact with the blocks 11 and 11' to the position 110 shown by dotted lines, thereby breaking the circuit. The light circuit wire 4' is ground-

ed through the contact lever 10, while the wire 5' is connected to the block 11. The telephone wire 7' is grounded through the contact lever 10' and the wire 6' is connected to the contact 11'.

The numeral 18 indicates a telephone connected in the usual way to the telephone wires 6 and 7. This telephone, as shown, is of the automatic type, involving the customary rotary disc 19, but in some cases, the said telephone may be of the manually operated type.

The numerals 21 and 21' indicate so-called "night" light bulbs, connected in one of the leads 4'—5' in such manner that, when it is turned out or removed or otherwise put out of action, the light-supplying current through the leads 4 and 5 will be cut off.

The numeral 22 indicates a magnet coil shown as connected in the lead 4' and constituting a part of an electro-magnetic switch, which further comprises a core 23, a frame 24, and a pivoted armature lever 25, which latter, when not subject to the magnet, will be raised by a coiled spring 26. The armature lever 25 carries a spring contact 27 that cooperates with a fixed contact 28.

The telephone wire 6' is intermediately sectioned and one end is connected to the movable contact 27 and the other end is connected to the fixed contact 28. When the magnet 22 is energized, the lever 25 will be held downward and the contact 27 will be separated from the contact 28, thus breaking the circuit in the line 6'—7'.

When this invention is used in connection with an automatic telephone system, we provide an automatic circuit maker and breaker connected in one of the leads of the shunt circuit 6'—7'.

Referring to Figs. 2 and 3, the numeral 30 indicates a disc adapted to be rotated on a shaft 31 by a spring 32 in a direction opposite to that of the hands of a clock, in respect to Fig. 2. The spring 32 is connected at one end with a sleeve 33 or other suitable anchorage that is adapted to be rotated manually and secured in different positions to keep said spring under tension, all by means in common use.

The disc 30 is provided near its circumference with a number of radial holes 34 suited to receive a plurality of pins 35, composed of a dielectric substance, that are arranged to represent chosen numbers and for the purpose of operating the corresponding automatic switches in the central station in the same manner as would be done by calling the same number in the usual operation of the telephone instrument.

In order to secure this result, spring contacts 36 are interposed in the circuit 7' and are adapted to be separated by the passage of the dielectric pins 35 between their con-

tacting ends. A magnetic coil 37 in circuit in the line 7' is provided with a solenoid core 38 attached at its outer end to an escapement lever 39, impelled by a spring 41 and normally engaging with an extension 40 on the circumference of the disc 30 and preventing the latter from rotating.

It will be evident from inspection that when the coil 37 is energized, the escapement 39 will be disengaged from the extension 40, permitting the disc 30, impelled by the spring 32, to rotate, thereby causing the pins 35 to successively separate the spring contact 36 and thereby successively interrupt the current in the line 7'. The radial pins 35 only extend around a portion of the circumference of the disc 30 and the latter continues to rotate, permitting the telephone bell to ring until the escapement 39 contacts with an extension 42 and the movement is arrested. Near the circumference of the disc 30, on the same radius as that of the pins 35, is secured a dielectric separator 43 so located that when the escapement 39 engages the extension 42, the separator 43 will be situated between the spring contacts 36 and so cause the ringing of the telephone bell to cease. When the telephone call is answered and no response is received, the one answering will thereby know that the current has been intercepted by turning off the night light.

In order to make the arrangement of the pins more readily understood we will assume, as an example, that an alarm station telephone is represented by the call B235, B being represented at central by 2. Then the pins 35 would be located, as shown in Fig. 2, with a sufficient space between each group to correspond with the time required for the usual manual operation. By this means, the switches at central will be operated to connect with the telephone B235 and the bell of the same will ring until the disc 30 comes to rest. To reset the disc 30 for operation, the escapement 39 is transferred from the extension 40. The speed of rotation of the disc 30 may be controlled by a governor, not shown, of any pattern such as are in common use on phonograph tables.

When it is desired to give the alarm at a station other than by telephone, a wire 6² may be carried from the contact 23 through a battery, transformer or other source of current 44 to a bell 45, returning through the wire 7² to the wire 7', thereby securing a continuous ringing of the bell 45 when the circuit is closed, due to the intercepting of the circuit current 4'—5'.

The wheels 8 and 8' carrying the time switches are operated in unison by the same clock work. To illustrate the operation, we may assume, as an example, that the arm 9

is positioned to operate the arm 10 at nine o'clock P. M., thereby turning on the lights 21 and 21', and energizing the magnetic coil 22 and separating the contacts 27 and 5 28. The arm 9² may be set to operate the arm 10' at nine-fifteen P. M., thus connecting the lines 6' and 7', but not closing the circuit because of the separation of the points 27 and 28.

10 The arm 9² is then set to operate the arm 10' at six o'clock A. M. and thereby disconnect the lines 6', and 7', and the arm 9' is set to operate the arm 10 at six-fifteen A. M., thereby turning off the lights 21 and 21'.

15 If, therefore, between the periods of fifteen minutes after nine in the evening and six o'clock in the morning, one of the lights 21 is turned off or the wire cut or the current in any way interrupted, the magnetic coil 22 will be energized, thereby releasing the magnet arm 23 and permitting the spring 26 to close the contact 27 against the contact 28 and complete the shunt circuit 6' and 7', operate the solenoid 38, and release the disc 30, giving the alarm over the telephone in the manner already explained. However, after the switch arm 10' has been disconnected from the block 11', it will be evident that the turning off of the light 21 30 will not cause an alarm on the telephone.

In case the ordinary telephone is used, instead of the automatic, the closing of the contact 27 against the contact 28 and consequent closing of the shunt circuit will cause 35 the central station to be signalled in the same manner as if the receiver were removed from the hook on the instrument. When central answers and receives no response, she will know by information previously given that one of the lights 21 has been turned off, and will call and notify the police, the proprietor or other parties as she may have previously been instructed.

What we claim is:

45 1. The combination with an electric light circuit, of an electric light bulb forming a part of said circuit, a timed switch adapted to automatically open and close said circuit, a shunted telephone circuit, means cooperating with said light circuit for closing said telephone circuit.

50 2. The combination with an electric light circuit, of means for opening said circuit, a shunted telephone circuit, a timed switch adapted to automatically open and close said telephone circuit, and means cooperating with said light circuit for closing said telephone circuit.

55 3. The combination with an electric light circuit, of an electric light bulb forming a part of said circuit, a timed switch adapted to automatically open and close said circuit, a shunted telephone circuit, a timed switch adapted to automatically open and close said telephone circuit and means cooperat-

ing with said light circuit for closing said telephone circuit.

4. The combination with an electric light circuit, of an electric light bulb forming part of said circuit, a timed switch adapted to automatically open and close said light circuit, a signal bell circuit, a timed switch adapted to automatically open and close said bell circuit, and means cooperating with said light circuit for closing said bell circuit. 75

5. In an electric signalling apparatus, the combination with an electric light circuit, of an electric bulb forming a part of said circuit, an electromagnet incorporated in said circuit, a shunted telephone circuit, a signal bell circuit, a timed switch for automatically opening and closing said telephone circuit and bell circuit, means whereby the telephone circuit and bell circuit are held open when the said electromagnet is energized, and means for closing the telephone and bell circuits when the electromagnet is deenergized. 80 85

6. The combination with an electric light circuit, of means for opening said circuit, a shunted telephone circuit, means cooperating with the opening of said electric light circuit for closing the said telephone circuit, and automatically operating means for successively opening and closing said telephone circuit in a prearranged order. 90

7. The combination with an electric light circuit, of means for opening said circuit, and an electromagnet incorporated in said circuit, a shunted telephone circuit, means cooperating with said electromagnet for closing said telephone circuit, automatically operating means for successively opening and closing said telephone circuit in prearranged order, and electrically controlled means for setting in operation the said means for successively opening and closing the telephone circuit. 100 105

8. The combination with an electric light circuit, of means for opening said circuit, a shunted telephone circuit, means cooperating with said electric light circuit for closing said telephone circuit, automatically operating means for successively opening and closing said telephone circuit in a prearranged order, and means for retaining said circuit open after the completion of the successive prearranged opening and closing operation. 110 115 120

9. The combination with an electric light circuit, of means for opening said circuit, a shunted telephone circuit, means co-operating with said electric light circuit for closing the telephone circuit, a timed switch adapted for opening and closing the telephone circuit, and automatically operating means whereby the telephone circuit is caused to be successively opened and closed 125 130 in a prearranged order.

10. The combination with an electric light circuit, of means for opening said circuit, a timed switch for opening and closing said circuit, a shunted telephone circuit, a timed switch for opening and closing said telephone circuit, means cooperating with said electric light circuit for closing said telephone circuit, and means whereby the said telephone circuit is caused to be 10 successively opened and closed in a prearranged manner.

11. The combination with an electric light circuit, of means for opening said

circuit, a shunted telephone circuit, means cooperating with said electric light circuit 15 for closing said telephone circuit, means for successively opening and closing said telephone circuit, in a definitely prearranged order, and means for varying the said order of successively opening and closing said 20 circuit.

In testimony whereof we affix our signatures.

NEWTON L. GLOVER.
JAMES A. HANSON.
